UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

HEADER MECHANISM.

Application filed July 1, 1921. Serial No. 481,849.

To all whom it may concern:

Be it known that I, RICHARD LESTER WILCOX, a citizen of the United States, residing at Waterbury, in the county of New Haven and State of Connecticut, have invented certain new and useful Improvements in Header Mechanisms, of which the following is a specification, reference being had therein to the accompanying drawings.

10 This invention relates to header mechanisms and refers more particularly to new and improved means for connecting and in part operating the punch slide or similar parts of a header or upsetting machine.

15 It is the object of this invention, among other things, to so associate the slide of a header or upsetting machine, with the means that give it relative movement upon the gate, that it is entirely unnecessary to regard the heretofore essential requirement of an exact angular relation of the parts, thus permitting all of the parts to operate efficiently without accurate machining and whereby the assembly of the parts is materially facilitated and the possibility of wear and breakage reduced to the absolute minimum.

20 The improvements in the details and arrangement of parts will be apparent from an inspection of the accompanying drawings in connection with the description hereinafter contained and wherein a preferred embodiment of the invention is disclosed for the purpose of imparting a full understanding 25 of the same.

In the drawings,—

20 Figure 1 is a side elevation of my improved mechanism, with so much of the adjacent parts of a header or upsetting machine of a well known type, as is essential to show its connection therewith;

Figure 2 is a front view thereof with some of the adjacent parts in section;

Figure 3 is a fragmentary elevation of a portion of an alternative form, wherein a single gib is used; and

Figure 4 is another elevation of the same mechanism.

In the drawings, wherein like reference characters refer to corresponding parts, 10 designates a portion of the body of a header, 11 the gate that has a reciprocatory movement therein beneath the caps 12, 13 a rock shaft journaled in the bearings 14 connected

with the body 10 and having a plate 15 55 upon one end thereof with which is adjustably secured a connecting device 16 through which motion is imparted to said rock shaft.

Forming part of the rock shaft 13 between the journal bearings 14 are the offset 60 arms 17, joined by the tie bar 30, within which is journaled the cradle 18.

All of the parts above described are common and well known in the header art and require no further description herein. 65

The punch slide 19, to which is adjustably secured the punch block 20 having the punches 21 fixed therein, is movably mounted in the front end of the gate 11. Slidably mounted in the cradle 18 is a shifter plate 70 22 held therein with proper frictional engagement by gibs 23 against which abut the adjusting screws 24.

A hinged connection is made between the punch slide 19 and shifter plate 22 by the 75 pin 25 that passes through lugs 26 on the shifter plate 22 and the lug 27 on the end of the punch slide 19. For convenience cotter pins 28 project through the outer ends of the pin 25 to prevent displacement 80 thereof, but other well known means may be adopted for this purpose if desired. While the pivotal connection shown and described is the preferred form thereof, it is possible, however, to substitute other 85 forms of such connection within my invention.

Heretofore, the punch slide 19 and the shifter plate 22 have been permanently secured together so that it is absolutely essential that the axis of the rock shaft 13 be at a right angle to the punch slide 19. If such was not the case the punch slide did not operate efficiently, frequently binding in its ways, causing unusual and unnecessary wear 90 on the parts, the fastening means therebetween frequently became broken by reason of the undue and unequal strains upon some of the parts and in other ways the improper alignment of the parts produced conditions 95 that were grossly unsatisfactory.

Machining of the parts to secure this right angle relation, increased with the size of the header, thus adding materially to the cost of the machine. Also if the right angle relation was not obtained, the bigger and more powerful the header the greater such objections became. 100 105

With my improvement, it is absolutely immaterial so far as the punch slide 19 is concerned whether the axis of the shaft 13 is in right angle thereto or not as the hinged connection between it and the shifter slide accommodates any inaccuracy.

In Figures 3 and 4 I have illustrated an alternative form of the cradle 18, having a single gib 23 therein instead of two as illustrated in Figures 1 and 2. The single gib is held against endwise movement by the pin 29, rather than by the overhanging lips at each end as in the form shown in Figures 1 and 2. Obviously these forms of gibs may be used interchangeably if desired.

Minor changes and alterations may be made within my invention, aside from those herein suggested, and I would therefore have it understood that I do not limit myself to the exact construction herein shown and described, but claim all that falls fairly within the spirit and scope of the appended claims.

What I claim as new and desire to secure by Letters Patent, is:

1. In a device of the character described, a gate; a punch slide on said gate; a shifter plate; a pivotal connection between said shifter plate and punch slide; and means for imparting movement to said shifter plate whereby said punch slide may be moved upon said gate in a path at an angle to that of said gate.

2. In a device of the character described, a body member; a shaft journaled therein; a gate movably mounted in said body; a punch slide on said gate; and flexible means between said shaft and punch slide for imparting movement to said punch slide upon said gate irrespective of the angle between the axis of said shaft and said punch slide.

3. A device of the character described having a gate, a punch slide movably mounted therein, a rock shaft, and means for imparting movement to said punch slide from said rock shaft comprising mechanism having a sliding and pivotal connection with said shaft.

4. A device of the character described having a gate, a punch slide movably mounted therein, a rock member, a shifter plate movably mounted therein, interlocking lugs upon said punch slide and shifter plate, and a pin connecting said lugs.

5. In a device of the character described, having a gate; a punch slide movably mounted thereon; a rock member; and a shifter plate movably connected with said rock member and in part moved thereby, having a hinged connection with said slide.

6. In combination with the gate of a device of the character described; a punch slide movably mounted thereon; and a shifter plate movable with said slide and having a hinged connection therewith. 65

7. In combination with the gate of a device of the character described; a punch slide movably mounted thereon; and a shifter plate movable with said slide and having a hinged connection therewith, the 70 axis of said hinged connection being substantially parallel with the direction of movement of said gate.

8. In combination with the gate of a device of the character described; a punch 75 slide movably mounted thereon; a shifter plate movable with said slide and means for connecting said shifter plate with said punch slide whereby the same may rock in one direction relatively thereto and be held 80 against movement in the opposite direction, said means comprising a hinge member connecting interlocking parts upon the slide and shifter plate.

9. In a device of the character described, a 85 reciprocating gate; a punch slide movably mounted thereon; a rock shaft; a connection between said rock shaft and slide whereby the movement of said rock shaft imparts a movement to said punch slide upon said gate 90 during the reciprocation thereof, said means comprising in part a member having an operative connection with said rock shaft and a hinged connection with said punch slide, said member moving as a unit with said 95 punch slide.

10. In a device of the character described, having a gate; a punch slide movably mounted thereon; a rock member; and a shifter plate movably connected with said 100 rock member and operated thereby, having a hinged connection with said slide, the axis of said member and that of said hinged connection being at substantially a right angle to each other. 105

11. In a device of the character described, a body member; a gate slidably mounted thereon; a shaft below said gate, the axis of which is at substantially a right angle to the direction of movement of said gate; a 110 punch slide movable upon said gate; and means between said shaft and said punch slide for imparting movement from said shaft to said punch slide upon said gate, said means comprising in part a hinge member, the axis of which is at substantially a 115 right angle to the axis of said shaft.

In testimony whereof, I have hereunto affixed my signature.

RICHARD LESTER WILCOX.
